EXTRUDED METAL UNIT ADAPTED FOR USE AS A HEAT SINK

Anton J. Horn, Creve Coeur, Mo., assignor to Biological Research, Inc., Bridgeton, Mo., a corporation of Delaware

Filed June 28, 1963, Ser. No. 75,615

Term of patent 14 years

(Cl. D26—1)

FIG. 1

FIG. 2

FIG. 3

FIG. 4

FIG. 1 is a bottom plan view of an extruded metal unit adapted for use as a heat sink embodying the design;

FIG. 2 is an end elevational view thereof;

FIG. 3 is a fragmentary top plan view thereof; and

FIG. 4 is a side elevational view thereof.

The center portion of the article in FIGS. 1, 3 and 4 has been broken away to indicate indeterminate length.

I claim:

The ornamental design for an extruded metal unit adapted for use as a heat sink, substantially as shown and described.
